UNITED STATES PATENT OFFICE.

MAGNUS E. STANGE, OF ST. PAUL, MINNESOTA, ASSIGNOR OF ONE-THIRD TO SIDNEY D. BUMGARDNER, OF ST. PAUL, MINNESOTA.

DUMPING-CAR.

1,086,336.

Specification of Letters Patent.

Patented Feb. 3, 1914.

Application filed June 23, 1913. Serial No. 775,370.

To all whom it may concern:

Be it known that I, MAGNUS E. STANGE, a citizen of the United States, residing at St. Paul, in the county of Ramsey and State 5 of Minnesota, have invented certain new and useful Improvements in Dumping-Cars; and I do hereby declare the following to be a full, clear, and exact description of the invention, such as will enable others skilled in 10 the art to which it appertains to make and use the same.

My invention relates to dumping cars of that type which are usually arranged to travel on rails and are used in making excavations and grading and which are provided with bodies or boxes mounted for lateral, pivotal dumping movements and have side gates arranged to be moved away from the sides of the car on the discharge side of 20 the tilted body.

Generally stated, the invention consists of the novel devices and combinations of devices hereinafter described and defined in the claims.

25 In the accompanying drawings which illustrate the invention, like characters indicate like parts throughout the several views.

Referring to the drawings, Figures 1 and 2 are views in end elevation, showing the 30 car embodying my invention and illustrating, respectively, the normal and dumping positions of the car body.

The car involves trucks 1, the wheels of which are arranged to run on rails 2. The 35 couplers 3, at the ends of the car are secured to or formed as part of end pedestals 4. The car body or box 5, at the transversely central lower portions of its ends, is provided with heavy hinge brackets 6 having depending lugs 7 that are pivotally connected to 40 extreme upper portions of the pedestals 3. This car body 5 is formed with open sides that are adapted to be closed by heavy side gates 8. Upright metal posts 9, preferably 45 in the form of angle irons, are rigidly secured to the edges of the front and rear ends of the body 5, and to the under frame structure 5^a of said body.

The side gates 8 are pivotally connected 50 to the outer ends of upper and lower supporting bars 10 and 11, respectively. The upper bars 10 are longer than the lower bars

11 and their inner ends are downwardly curved and pivotally attached to the end brackets 6 at 12. The pivots 12, by means 55 of the brackets 6, are indirectly secured to the ends of the car, near the bottom thereof and at points in the immediate vicinity of its transversely central portions. In fact, the said pivots 12 might be coincident and located at the exact transverse center of the car. The inner ends of the relatively short lower bars 11 are connected by supporting links 13 to the inner end portions of the upper bars 10. Thrust links 14, pivotally connect 60 the inner ends of the said lower bars 11 to the central portions of the ends of the car body 5 at 15. The said pivots 15 are located above the pivots 12 and are preferably directly pivoted to the metallic straps or extensions 16 of the end brackets 6.

Gate lifting bars 17 are pivotally connected at their upper ends to intermediate portions of the upper gate supporting bars 10, and their lower ends are adapted to engage 75 with stop plates 18 secured on the side end portions of the frame of the truck 1. It may be here stated that the car above described, may involve one or more trucks 1, depending on the length of the car. Guide 80 links 19 are pivotally connected at their outer ends to the intermediate portions of the posts 17, and at their inner ends, are pivotally connected to depending lugs 20 of the end brackets 6.

The car body or box 5, when in its horizontal or normal position shown in Fig 1, and both when loaded and when empty, will be approximately balanced or in a neutral position. It is normally held against pivotal 90 dumping movements by chains 21, shown as attached at their upper ends to the sides of the under frame 5^a and attached at their lower ends to the sides of the frame of the truck 1. These chains 21 are made in sections, the upper sections, as shown, having hooks 22 that are detachably engageable with links of the lower sections. When it is desired to dump the car body, the sections of the chains on the opposite side from 100 which it is desired to dump, must be uncoupled, and then the car body will be free to dump or tilt into a discharging position shown in Fig. 2. Under a tilting movement

of the car body from the position shown in Fig. 1 into the position shown in Fig. 2, the gate 8 on the rising side of the body remains in a closed position, but the gate on 5 the lower side is opened with an accelerated movement produced when the gate tripping bars 17 on the lowered side, engage with the stop plates 18 of the truck. When this engagement between the bars 17 and plates 18 10 takes place, downward movement of the gate 8 on the lowered side of the car body ceases, and as the pivot 12 on that side continues to lower, the bars 10 operate as levers having a fulcrum on their upper ends of the bars 17, 15 and thereby produce an upward movement of the said gate. More than this, the pivot 15 moves rapidly toward the right, in respect to Fig. 2, and thereby gives to the lower edge portion of the open gate a rapid 20 outward swinging movement, so that the said gate is thrown into an oblique position shown in Fig. 2. This movement very greatly increases the rapidity with which the open gate recedes from the open side of 25 the body, and hence, gives a quick and very free dumping action. Furthermore, with the arrangement described, all strains due to the weight of the gates and to the pressure of the dirt thereon is transmitted directly to the end brackets 6, and from thence to the subframe structure 5^a of the car body. Thus I eliminate an objectionable action 30 which takes place in various other dumping cars of this general character, to-wit, tendency to rack the ends and corner post of the car body, due to pivotal connections directly between the upper portions of the end boards or members, and the gate supporting connections. Obviously, also, a freer 35 and much greater dumping action is produced by my improved gate supporting connections, which move the gates both with an upward and angular outward swinging movement on the dumping side of the car, 40 and thus obtain a very quick and complete 45 opening movement.

What I claim is:

1. In a dumping car, the combination with a supporting truck, and a car body intermediately pivoted thereto for lateral dumping movements, of gates coöperating with the sides of said car body, upper and lower bars pivotally connected to said side gates at their outer ends, said upper bars 50 having inner ends pivotally connected to the lower central portions of the ends of said car body, supporting links pivotally connecting the inner ends of said lower bars to the said upper bars, thrust links pivotally connecting the inner ends of said lower bars 55 to the central portion of the car body, and gate lifting bars pivotally connected to one of the said gate supporting bars and en-

gagable with the truck frame, and operative to impart an upper and outer angular 65 swinging movement to the side gate on the lowered side of the car body.

2. In a dump car, the combination with a car truck and a body intermediately pivoted thereto for lateral dumping movements, said car body having end brackets centrally secured to the lower portions of the ends thereof, side gates for normally closing the sides of said car body, upper bars pivotally connected at their outer ends 70 to the upper portions of the ends of said side gates and having their inner ends downturned and pivotally connected to the end brackets of said car body, lower links pivotally connected at their outer ends to the lower end portions of said side gates, links connecting the inner ends of said lower bars 75 to the intermediate portions of said upper bars, thrust links pivotally connected to the inner ends of said lower bars and to the 80 central portions of the ends of said car body.

3. In a dump car, the combination with a car truck and a body intermediately pivoted thereto for lateral dumping movements, said car body having end brackets 90 centrally secured to the lower portions of the ends thereof, side gates for normally closing the sides of said car body, upper bars pivotally connected at their outer ends to the upper portions of the ends of said side gates and having their inner ends downturned and pivotally connected to the end brackets of said car body, lower links pivotally connected at their lower ends to the lower end portions of said side gates, links 95 connecting the inner ends of said lower bars to the intermediate portions of said upper bars, thrust links pivotally connected to the inner ends of said lower bars and to the central portions of the ends of said car body, 100 and gate lifting connections attached to certain of the gate supporting bars and engageable with portions of the car truck to lift and swing outward the gate on the lowered side of the car.

4. In a dump car, the combination with a car truck and a body intermediately pivoted thereto for lateral dumping movements, said car body having end brackets centrally secured to the lower portions of the ends thereof, side gates for normally closing the sides of said car body, upper bars pivotally connected at their outer ends to the upper portions of the ends of said side gates and having their inner ends downturned and pivotally connected to the end brackets of said car body, lower links pivotally connected at their lower ends to the lower end portions of said side gates, links connecting the inner ends of said lower bars 115 to the intermediate portions of said upper 120 bars.

bars, thrust links pivotally connected to the inner ends of said lower bars and to the central portions of the ends of said car body, gate lifting bars pivotally connected at their upper ends to the upper gate supporting bars, links connecting said lifting bars to portions carried by the said car body, and stop plates on the sides of the truck frame

with which the said lifting bars are engageable, substantially as described.

In testimony whereof I affix my signature in presence of two witnesses.

MAGNUS E. STANGE.
